UNITED STATES PATENT OFFICE.

GEORGE RICHARD BARR, OF HACKNEY, LONDON, ENGLAND.

AUTOMATIC COIN-OPERATED MACHINE.

Application filed August 12, 1922, Serial No. 581,403, and in Great Britain November 22, 1921.

My invention relates to an automatic machine for playing a game, representing football or the like, and comprises a construction of the kind having a series of figures distributed over a field or playing ground at each end of which is provided a goal, the figures being associated with operating levers through which a ball is impelled over the playing surface toward one or other of the goals. Coin-released mechanism is usually provided to enable a ball to be released to be played with, and mechanism is arranged to return a coin if the ball is projected into either goal. In the apparatus hitherto proposed, however a single coin is employed which forms part of a train of gearing, the operation of which enables a ball to be delivered at the centre of the playing surface. In a cricket game apparatus it has also been proposed to release the mechanism by the insertion of two separate coins into a single coin chute one of said coins being returned at the end of the game and the other retained.

According to this invention I construct my machine of a suitable frame, having an upper surface which acts as the playing ground upon which the game is placed and upon which a series of figures are mounted in suitable positions to form two opposing teams substantially as in a game of football or the like. These figures are arranged in groups to represent forwards, half-backs, backs and a goal keeper for each side, or any other suitable arrangement. Each figure is provided with a movable limb, such as one leg which is pivoted and adapted to be operated to impel or kick the ball toward the opposite end of the field, with the object of sending it into the opponent's goal. Each group of figures is connected to an operating lever of which a series are provided upon the outside of the machine and adapted to be actuated by each of the two competitors playing the game. Each lever is mounted upon the end of a transverse pivoted rod so as to move the limb or leg of the figures when it is turned about its axis.

Each figure is mounted in a depression in the field so that the ball will roll down to the feet of one of the players ready to be impelled toward the opposite goal when the foot of that figure is actuated. The goal at each end is formed with a sloping surface leading to a hole through which the ball passes when a goal is scored. Both these holes lead to a common channel along which

the ball rolls and down a chute to the bottom of a column of balls ready to be again used when its turn comes.

Separate slots are provided for the insertion of two coins, one of which releases mechanism to allow the uppermost of a column of balls to be passed out through a suitable aperture into the centre of the field. The other coin is held in a position ready to be released when a goal is scored, and the competitor who scores the goal will receive the returned coin.

One of the coins inserted into the machine is adapted to release mechanism which enables one of a series of balls arranged in a pile to be delivered onto the playing surface, and when a goal is scored by either player, the ball is returned through a chute to the bottom of the pile, and means are provided in the path of the returning ball to operate mechanism which will release the other coin and deliver the same to the person scoring the goal.

In order that my invention may be readily understood, reference is made to the accompanying drawings which show by way of example a construction of the apparatus according to the invention.

Figure 1 is a front elevation of the apparatus.

Figure 2 is a plan view of the field or playing surface.

Figure 3 is a view to an enlarged scale showing one of the players and the mechanism for operating the same for manipulating the ball over the playing surface.

Figures 4 and 5 are plan view and under-plan respectively of one of the shutter like members with which the playing figures are associated.

Figure 6 is a sectional plan view taken immediately below the playing surface.

Figure 7 is a vertical section on the line A—B of Fig. 6.

Figure 8 is a detail view of the releasing pawl for enabling one of the balls to be delivered onto the playing surface.

Figure 9 is a sectional view to a larger scale showing a portion of Figure 6.

Figure 10 is a part sectional elevation of the inner side of the front of the enclosing casing for the mechanism, the parts being shown to a larger scale.

The apparatus illustrated in the drawings shows the application of the invention to a football game and comprises a casing 15 of

any suitable shape and size, the upper portion of which is provided with glazed sides 16 located around a playing surface indicated at 17. The playing surface 17 is constructed to represent as nearly as possible a normal football playing field in miniature and the said surface is provided with a plurality of pivotal shutter like members 18 located in groups on each half of the playing surface, the groups being preferably arranged to represent forwards, half backs, backs and goal keepers of two teams of players. At each end of the field is a goal 17^a hereinafter referred to.

15 In the construction shown in the drawings, the pivotal shutters 18 are of rectangular shape, and the figures 19 representing the players are rigidly fixed to the playing surface, and preferably in such a manner 20 that they are supported by one leg 20 on a portion of the stationary playing surface, whilst the opposite leg 21 is pivoted to the body of the figure. The shutter like devices 18 are each a loose fit in the corresponding 25 recesses 18^a formed in the playing surface, so as to ensure free movement thereof. Preferably the shutters 18 are pivoted along one of their longitudinal sides, that is the side opposite to that adjacent which the 30 playing figures 19 are fixed so that during their movement, the pivotal legs of the playing figures are moved to imitate as far as possible the movement of a player kicking a ball. The shutters 18 are preferably provided with a weighted under surface 22 to ensure their returning to the normal position.

35 The playing surface is formed with an irregular upper surface, that is to say the portions of the playing surface surrounding each of the recesses in which the shutters are located and around the mouth of the goals, is dished or inclined towards the edges of said recesses, so that the ball has a natural 40 tendency to roll onto the shutters when being played. This is clearly shown in Figures 1 and 3.

45 Beneath each of the recesses 18^a for the shutters is a supporting bracket 23, on which 50 is pivotally mounted a two armed lever 24, one arm of said lever engaging the under-surface of the weighted portion of the shutter whilst the opposite arm is connected by a rod 25 to an arm 26 rigidly fixed to one of a 55 series of horizontal rods 27 extending across the casing 15 from the front wall towards the rear wall. These rods or shafts 27 are located at spaced intervals apart and are provided at their forward ends which extend 60 through the front wall of the casing 15, with operating handles or thumb pieces 28 which enable the same to be oscillated in their bearings. I prefer to provide three such rods or shafts 27 for each team, that is six in all and two of the shafts of each team

each control say four of the playing figures, whilst the remaining shaft controls three playing figures. It will thus be seen that by rotating the shafts 27 by means of the thumb pieces 28, the shutters are lifted, and in so doing the ball for the time being resting upon a shutter is flicked or impelled over the playing surface and may come to rest on any of the other shutters, and each player has to exercise his skill in manipulating the shafts 27 in such a manner that the ball is impelled towards and into the goal mouth of the opposing player. The movement of the shutters 18 in an upward direction is caused by the rotation of the shafts 27 in the direction indicated by the arrow in Figure 3, and in so moving, the upper surface of the shutters come into contact with the free end of the pivotal leg of the playing figures and move the same in a very realistic manner 85 and the movement of the movable legs of the playing figures assists to a certain extent in the flicking of the ball over the playing surface.

90 The ball is delivered onto the playing surface at a point located at the centre thereof. The mechanism for feeding the ball onto the playing surface comprises a vertically disposed tubular chute 30, two oppositely disposed walls of which are slidable 95 with relation to the remaining walls. The chute is preferably rectangular in shape and the stationary walls are adapted to form guides for the movable walls. One or both of the movable walls of the chute is provided with a gravity or spring operated trigger or the like 41 located near the base of the chute. Within the chute are arranged a series of balls superimposed upon one another, and beneath the pile of balls is a platform 32 which is adapted to be raised by means of a rod 33 pivotally connected at its lower end 34 to the platform 32 and connected at its upper end to a pin 35 carried by a disc 36 fixed to a rotatable shaft 37 extending transversely from front to back of the casing 15. The forward end of the shaft 37 carries a knob or button 38 to enable the same to be rotated, and the said shaft is preferably located centrally beneath the playing surface 17. 33 is a rod or link the lower end of which is pivoted to the movable or slidable sides of the ball chute whilst its upper end is provided with a longitudinal slot engaging the pin 35 on the disc 36. By this means when the shaft 37 is rotated by the knob 38, the disc carrying the pin 35 rotates and raises the rod 33 and with it the platform 32 with a ball resting thereon. During the preliminary upward movement of the platform 32, the vertically slideable walls of the ball chute remain stationary and when the ball resting on the platform 32 reaches a height to be engaged by the pivotal trigger 41 the pin on the disc 36 100

130

engages the upper end of the slot in the link 53 and during the further rotation of the shaft 37, the link 53 is also raised and carries with it the column of balls, and the height through which this column of balls is raised is equal to or slightly greater than the diameter of one of the balls. By this means, the uppermost ball of the pile is raised to such a position that it is able to roll onto the 10 playing surface. When the column of balls is again lowered, the trigger 41 supports the column of balls and the platform 32 returns to its lowermost position ready to receive the ball previously delivered onto the playing 15 surface, after the same has been impelled into one of the goals and thence through the chutes now about to be described.

Within each of the goals 17^a is an aperture 42 leading to a chute 43, and each of the 20 chutes 43 extends towards the centre and beneath the playing surface and communicates with a common chute or passageway 44 (Figs. 2 and 7). The lower end of the chute 44 is provided with a lateral extension 45 leading 25 to the bottom of the tubular member 30 which is suitably apertured for that purpose, and when the ball is impelled into either goal, it rolls into the aperture 42 along the corresponding chutes 43, 44 and 45, and ultimately comes to rest on the platform 32, 30 the column of balls in the tubular member 30 being supported by the trigger or the like 41, so that when the column of balls is again raised by the platform 32, the ball last delivered through the return chutes 43, 44 and 45 is raised and becomes the lowermost of the column of balls.

Towards the lower end of the chute 44 for 40 the return balls is a pivotal weighted lever 46 which is adapted to be rotated about its pivot by the passage of a ball through said chute, and this lever operates through a rod 47, a coin releasing pin hereafter described.

Located within the casing are two coin chutes 48 and 49 respectively each of which terminates in the front wall of the casing at the coin slots 48^a and 49^a, while one of said chutes leads to a return delivery chute 50 terminating at 51 (Figs. 1 and 7) in a receptacle pocket or the like into which one of the coins, that is the coin inserted into the chute 48, is delivered at appropriate times. The other coin chute 49 leads to a container (not shown) located within the interior of the casing. Towards the lower end of the coin chute 48 is slidably mounted a pin or rod 52 extending transversely into the coin chute so as to retain a coin passing through 55 said chute, and this pin is connected to one end of the rod 47 which as previously described is connected to the pivotal lever 46, so that when a ball passes through the return ball chutes 43, 44 and 45, this lever will be operated to withdraw said pin 52 from the

coin chute 48 to allow the coin to pass on and be delivered through the chute 50 to the receptacle.

The rotatable shaft 37 has fixed thereto on the inner side of the front wall of the 70 casing 15, a ratchet wheel 55, a disc 56, and a brake disc 57. The ratchet wheel 56 (Fig. 8) has co-operating therewith a spring operated pawl 58 located to prevent at all times rotation of the shaft 37 in one direction. 75 The disc 56 has a portion of its periphery cut away to form a circumferential recess and the forward end, that is the leading end in the direction of rotation indicated by the arrow is adapted to form a tooth with which 80 engages one end of a pivotal lever 59 mounted on a pivot 60. The opposite end of the lever 59 is pivotally connected to a rod 61 the lower end of which is pivoted to a pivotal counterbalanced lever 62 rotating about 85 a pivot carried by a bracket 63. One end of the lever 62 extends into the coin chute 49 (see Figures 6, 7 and 10) in such a manner that the coin inserted into said chute depresses said lever and rotates the same to 90 a limited extent about its axis but without releasing the coin. This movement of the pivotal lever 62 is sufficient to exert a downward pull upon the rod 61 and consequently release the end of the pivotal lever 95 59 from the disc 56 so that the shaft 37 can be rotated. The disc 56 also carries adjacent its periphery a projecting pin 64 which, when the shaft 37 is rotated, comes into contact with a lateral extension 65 on the 100 pivotal lever 59 and causes a further partial rotation of the lever 59 and consequently a depression of the rod 61, which causes a further partial rotation of the pivotal counterbalanced lever 62.

Mounted adjacent the pivotal lever 62 is an inclined stationary bracket 66 provided with an elongated vertically disposed slot through which the weighted end of the lever 62 extends and in which it is adapted to move. Mounted slidably on this inclined bracket is a sliding member 67 the lower end of which is weighted and this sliding member is also provided with a longitudinal slot through which the lever 62 extends. The length of the slot is such that when the lever 62 is given its initial rotary movement, said sliding member 67 remains stationary, the end of the slot therein acting as a stop to limit the rotary movement of the lever 62 and hence prevent the operating coin in the chute 49 being released. When however the shaft 37 has been rotated through a sufficient distance to bring the pin 64 into contact with the extension 65 of lever 59, the downward movement of the rod 61 causes further rotary movement to be imparted to the counterbalanced lever 62 and during this secondary movement the sliding member 67 is raised in its bracket, 110 115 125 130

and the coin in the chute 49 is released and falls downwardly into a receptacle herein before referred to provided for the coins. Extending into and through the coin chute 48 is one arm 70^a of a weighted lever 70 mounted to pivot about a pin 71 carried by a bracket 72. This lever 70 is provided with three arms, one of which 70^a extends into the coin chute 48 and carries an adjustable weight 73, the second arm 70^b extends downwardly into close proximity to the lever 62, whilst the third arm has pivotally connected to the end thereof a shutter 74 mounted in guides at the base of the return ball chute 44, at the junction of the latter with the chute 43 leading to the platform 32. The arm 70^a of the lever 70 which extends into the coin chute 48 is normally above a pivotal sector shaped member 75 supported on a pin 76, and this member acts under its own weight to normally prevent more than a limited rotation of the lever 70. 77 is a depending rod mounted on a pin 78 the lower end of which carries an extension 79 which, when said rod is swung in a vertical plane about its pivot 78 is adapted to contact with the sector shaped member 75 and move the same out of the path of the pivotal three-armed lever 70. The depending rod 77 is adapted to be so moved by a pin 64 on a disc 56 which when the shaft 37 is rotated, moves said rod to the position shown by dotted lines in Fig. 10 thus disengaging the member 75 from the lever 70 and allowing the latter to be rotated a further amount under the weight of the coin in the chute 48. The pin 64^a is suitably bent to clear the extension 65 of the lever 59. The depending arm 70^b of the lever 70 normally extends into the path of movement of the lever 62 but when a coin is inserted into the coin chute 48 the lever 70 is rotated about its pivot so that the arm 70^b is moved out of the path of the lever 62 at the same time raising the shutter 74 and allowing a ball in the bottom of the chute 44 to pass into the chute 45 and onto the platform 32. On the coin being released by the lever 70, it falls downwardly and is retained by the pin 52 as previously described, while the pivotal lever 70, returns to its normal position. When the shaft has been rotated through a sufficient distance to allow the depending rod 77 to return to the position shown in full lines in Fig. 10, the sector shaped member 75 returns to its normal position. The weighted lever 62 which has also been moved to a position to release the coin in the chute 49 will also return to its normal position, and as this lever is connected by the rod 61 to the lever 59, the latter will engage the end of the cut away portion of the disc 56 as soon as the shaft 37 has been rotated through a complete revolution.

65 The apparatus is inoperative unless a

coin is inserted into each of the chutes 48 and 49. For instance if a coin is placed in the slot 48 and not in the slot 49, the coin will depress the arm 70^a on to the sector plate 75 and since the lever 59 will prevent 70 rotation of the shaft 37, the depending rod 77 cannot be operated to disengage the sector shaped member 75 from the lever 70. If a coin is inserted into the chute 49 and not in the coin chute 48, the shaft 37 will be released by the pawl but cannot be rotated since the pivotal three armed lever 70 is in a position to prevent movement of the lever 62 and furthermore the shutter 74 at the base of the return ball chute 44 cannot open to allow a ball to pass through the chute 45 onto the platform 32, so that even if the platform 32 is raised, no ball will be delivered onto the playing surface.

Referring now to disc 57, this disc is 85 also cut away over a portion of its periphery, and the remaining portion is adapted to be engaged, when the shaft 37 is rotated, by one end of a pivotal lever 80 (see Fig. 10) 90 which is under the control of a relatively powerful spring 81, and the periphery of the disc 57 engages the end of the lever 80 and rotates the same about its pivot against the tension of the spring, so that too rapid rotation of the shaft 37 is prevented. 95

The whole mechanism is suitably enclosed in the casing 15 provided with suitable doors to enable access to the mechanism to be obtained. The shafts 27 by which the shutters 18 are operated to impel the ball over the playing surface are provided with a lateral lug or pin 85 (Fig. 10) which co-operate with stops 86 to limit the oscillatory motion thereof.

The playing field is provided with figures 87 which represent linesmen and with a figure 88 representing the referee. The figure 88 may be mounted to be rotated by suitable means by one or more of the shafts 27. 105

It will be understood that while I have shown and described the apparatus as applied to a miniature football game, the apparatus may be constructed for other games such as hockey, cricket or like, suitable modifications being made in the operating mechanism. 110

115 I claim:

1. A coin operated machine for playing games by means of a ball, said machine being provided with a playing surface and means to project a ball on to said surface, two separate coin chutes, a series of playing balls mounted in pile formation beneath said playing surface, a rotatable shaft, a member beneath said pile of balls connected to said shaft by link mechanism, so as to raise the pile of balls and deliver the uppermost ball on to the playing surface when said shaft is rotated, and means associated 120 with said coin chutes whereby the rotatable 125

shaft is released for manual rotation on the passage of coins through said chutes.

2. A coin operated machine for playing games by means of a ball, said machine being provided with a playing surface and means to project a ball on to said surface, two coin chutes, means associated with said coin chutes for releasing the mechanism for delivering the ball onto the playing surface, means associated with one of said coin chutes for retaining the coin therein until the ball has been placed in a predetermined position, means for then releasing the coin, and means operated by the release of said coin for rendering the whole mechanism inoperative.

3. A coin operated machine for playing games by means of a ball, said machine being provided with a playing surface and means to project a ball on to said surface, coin chutes for the reception of a plurality of coins, mechanism operated by the passage of the coins through said chutes for releasing the delivering mechanism for the ball, means in said coin chutes for arresting the passage of the coins therethrough, said playing surface having apertures in the neighbourhood of its ends, a chute associated with said apertures down which the ball can pass, means associated with said ball chute for releasing one of the coins and returning said coin to the operator, and means for retaining the ball until coins have been inserted into both coin chutes.

4. A coin operated machine for playing games by means of a ball, said machine being provided with a playing surface and means to project a ball on to said surface, two coin chutes, said ball projecting means being controlled by the insertion of a coin in each chute, a ball tube beneath said playing surface, said tube having two slidable sides, a trigger carried by said slidable sides, means for raising said sides, a platform beneath said tube, a return ball chute leading from the playing surface to said platform, means for raising said platform, and operating means for first raising the platform and subsequently raising the ball tube.

5. A coin operated machine for playing games by means of a ball, said machine being provided with a playing surface and means to project a ball on to said surface, two coin chutes, said ball projecting means being controlled by the insertion of a coin in each chute, a ball tube beneath said playing surface, said tube having two slidable sides, a trigger carried by said slidable sides, a link for raising said sides, a platform beneath said tube, a return ball chute leading from the playing surface to said platform, a rod

for raising said platform, an operating shaft, and a crank pin associated with said shaft and engaging a slot in said link and also engaging said rod.

6. A coin operated machine for playing games by means of a ball, said machine being provided with a playing surface and means to project a ball on to said surface, a ball tube beneath said playing surface, a platform beneath said tube, a return ball chute leading from the playing surface to said platform, means for raising said platform, two coin chutes, a shutter in said return ball chute, an operating lever for said shutter, a retaining device for said lever, and means associated with one coin chute for releasing said retaining device, said operating lever projecting into the other coin chute so as to be moved by a coin therein after said retaining means has been released.

7. A coin operated machine for playing games by means of a ball, said machine being provided with a playing surface and means to project a ball on to said surface, a ball tube beneath said playing surface, said tube having two slidable sides, a trigger carried by said slidable sides, a link for raising said sides, a platform beneath said tube, a return ball chute leading from the playing surface to said platform, a rod for raising said platform, an operating shaft, a crank pin associated with said shaft and engaging a slot in said link and also engaging said rod, two coin chutes, a shutter in said return ball chute, an operating lever for said shutter, a retaining device for said lever, a stop for said operating shaft, means associated with one coin chute for releasing said stop, and means associated with the operating shaft for releasing said retaining device, said operating lever projecting into the other coin chute so as to be moved by a coin therein after said retaining means has been released.

8. A coin operated machine for playing games by means of a ball, said machine being provided with a playing surface and means to project a ball on to said surface, a ball tube beneath said playing surface, a platform beneath said tube, a return ball chute leading from the playing surface to said platform, means for raising said platform, an operating shaft controlling said raising means, a stop for said operating shaft, a lever projecting into one coin chute and operable by a coin therein, said lever controlling said stop, a stop for said lever, and means associated with the other coin chute for releasing said lever stop to permit a further movement of said lever to allow the coin to pass it.

GEORGE RICHARD BARR.
